UNITED STATES PATENT OFFICE.

WALTER J. BELL, OF LOS ANGELES, CALIFORNIA.

DESIGN FOR AN ELECTRIC SWITCHBOARD.

43,026.

Specification for Design.

Patented Sept. 17, 1912.

Application filed January 22, 1912. Serial No. 672,787. Term of patent 14 years.

To all whom it may concern:

Be it known that I, WALTER J. BELL, a citizen of the United States, residing at the city of Los Angeles, county of Los Angeles, and State of California, have invented a new, original, and ornamental Design for Electric Switchboards, of which the following is a specification, reference being had to the accompanying drawing, forming a part hereof.

The figure is a plan view of a dental electric switch board showing my new design.

Mounted on the base 2 of the insulating material at the top are the lamps 3 of which there are four, which project outwardly from the face of the base. Below the lamps and centrally transversely the base is a small clock 4, the face of which is slightly projecting from the face of the base. Below the clock and at each side of the base are pull switches, the knobs 5 of which project from the face of the base. At the sides of the knobs are name plates 6 on which

are engraved the names (not given) of the respective switches. A controller 7 is placed below the clock. The contact points and the switch of the controller project from the face of the base. Gages 8 and 9 are placed one at each side of the base and below the controller. The faces of the gages project slightly from the face of the base. An air regulator has its knob 10 projecting from the face of the base. Air regulating cocks 12 and 13 project from the face of the base at the lower corners.

I claim:

The ornamental design for an electric switch board as shown and described.

In witness that I claim the foregoing I have hereunto subscribed my name this 16th day of January, 1912.

WALTER J. BELL.

Witnesses:

FRANK WATERFIELD,
G. E. HARPHAM.
